AUTOMATIC FIREARM

Charles Sutter, Suresnes, and André Boussel, Courbevoie, France, assignors to Société Anonyme Anciens Etablissements Hotchkiss & Cie, Levallois-Perret, France, a joint-stock company of France

Application August 13, 1936, Serial No. 95,880
In Germany January 25, 1936

10 Claims. (Cl. 89—27)

To increase the rate of firing of automatic firearms it is customary to use resilient elements which store up the energy possessed, at the end of its recoil, by the breech closure mechanism of the firearm, and restore it to the latter at the beginning of its return to battery.

During continuous firing, devices of this kind do not increase the strain on the parts of the firearm. But when it is desired to cease firing, the sear has to stop the breech-closure mechanism which is moving at high speed, and is thereby subjected to considerable strain which can cause its breakage or that of other parts; owing to this fact, it is advantageous to damp this shock on the sear by making the latter resilient.

The invention relates to an arrangement which enables the same member to be used as a speed accelerator and as a damper for the sear.

According to the invention, the mechanism of the firearm is subjected to the action of accelerating members consisting of resilient elements (springs, Belleville washers, rubber, etc.) which serve at the same time as damping members for the sear when the firing is stopped.

For this purpose, the sear is carried by a movable member which can be displaced in the direction towards which, when the firing is stopped, the sear is urged against the action of the above mentioned resilient elements, which constantly tend to hold the said movable member and the sear in their normal position.

The resilient elements are interposed between a part on which the breech-closure mechanism acts at the end of the recoil, and a part which follows the displacements of the movable member carrying the sear, each of said parts being adapted to form an abutment for the resilient elements when they are compressed by the other part.

According to a modification, the resilient elements constantly bear against the same fixed abutment and are compressed in the same direction by the mechanism of the firearm and by the movable member carrying the sear.

According to an embodiment, the movable member comprises a sliding member carrying a pin on which the sear pivots.

Said sliding member carries a heel which forms one of the bearing parts of the resilient elements.

According to a modification, the sliding member itself contains the resilient elements which are in that case placed between two members either of which strikes fixed abutments when said sliding member moves, the latter moving in one direction or the other, from a mean position, according to

whether the resilient elements operate as a rate accelerator or as a sear damper.

According to another embodiment, the movable member comprises one or a plurality of oscillating levers fulcrumed about a fixed pin and which are pivotally connected to the sear, so that for any forward displacement of the latter there corresponds an oscillating movement of said lever or levers, which movement takes place against the action of the resilient elements.

The sear spring is placed between the sear and a fixed member, and a knuckle guide or a sliding guide is interposed between said spring and said member.

According to a modification, said spring is interposed between the sear and the movable member which carries it.

Other characteristics and peculiarities of the invention will become apparent from the ensuing description taken in conjunction with the accompanying drawings which show diagrammatically and merely by way of example various embodiments of the invention.

In said drawings:

Figs. 1 and 2 are sectional elevations of a first embodiment of the invention, Fig. 2 being a sectional view along the line II—II of Fig. 1.

Fig. 3 is a sectional elevation and, Figs. 4, 5 and 6 are plan views of another modification showing the members in the three different positions which they can take up.

Figs. 7, 8, 9, and 10 are sectional elevations of four other modifications.

In the embodiment of Figs. 1 and 2, the rate accelerator of the firearm comprises a member 1 subjected to the action of resilient elements 2 which can be of any kind (springs, rubber, Belleville washers, etc.). When the breech 3 reaches the end of its recoil, it strikes said member 1 and compresses the resilient elements 2 which thus store up a certain amount of energy, which they subsequently restore to the breech 3 at the beginning of its following forward travel, thereby causing an increase of the firing rate.

According to the invention, said resilient elements 2 not only operate for increasing the firing rate, but also play the part of a sear damper. For this purpose, the sear 4 is mounted on a pin 5 carried by a sliding member 6 mounted so as to be subjected to the action of the resilient elements 2. For this purpose, said member 6 is provided with a heel 7, and it is on said heel that the said elements 2 bear. The assembly formed by said elements 2, the buffer 1 and the heel 7, is lodged in a fixed casing 8 which includes an

abutment 9 against which can bear the collar 10 of the accelerator 1. The member 6 abuts at the rear, at the left of Fig. 1, against a fixed part 16 of the firearm. The initial compression of 5 the elements 2 is obtained by means of a nut 11, which screws on the threaded end of the rod 12 secured to the accelerator 1.

In the usual manner, the sear 4 is actuated by a trigger 26 and has a nose 13 on which hooks 10 the nose 14 of the piston 15 of the firearm, when the firing ceases.

The operation takes place under the following conditions:

As long as the firing goes on, the elements 2 15 operate exclusively to increase the firing rate, bearing, for this purpose, against the heel 7 that is to say against the sliding member 6 which itself bears against the fixed part 16 of the firearm.

When, for ceasing fire, the sear 4 is released, 20 the piston 15, at the beginning of its forward movement, hooks onto the nose 13 and tends to carry the sear 4 and consequently the member 6 forwards. The elements 2 damp this movement, bearing for this purpose against the collar 10 25 which itself bears against the abutment 9. By means of said damping, the strains to which the parts of the firearm are subjected when the firing stops are considerably diminished.

The sear spring 17 is, according to the invention, mounted on a knuckle guide 18 so that it can turn freely when the damped forward movement of the sear takes place.

As shown in Fig. 2, two accelerators 1 with a single sliding member 6, can be advantageously provided.

The invention can, moreover, be carried out with a great number of modifications and it is only by way of example that some other modifications of same will be described.

40 In the example of Figs. 3 to 6, the member 6 is integral with the casing 8 which, in this case, is therefore movable. Said casing has two bores in each of which is arranged an accelerator-damper assembly formed by the resilient elements 45 2, by a first head 1 playing the part of an accelerator and by a second head 7, playing the part of the heel 7 of Fig. 1. A threaded plug 11 enables the initial compression of the elements 2 to be effected. The united assembly comprising the 50 casing 8 and member 6 is provided with a nose 19 which is struck by a part 15 belonging to the moving mechanism of the firearm at the end of its recoil.

The operation takes place under the following 55 conditions:

Normally the damping members are in the position shown in Fig. 4. When at the end of the recoil, the part 15 strikes the nose 19 the assembly 8-6 is displaced towards the left and comes 60 into the position of Fig. 5 thereby compressing the elements 2 against the head 7. The energy stored up by said elements is restored to the mechanism of the firearm during the following stroke as previously described. During the firing 65 the members are thus displaced at each shot between the position of Fig. 4 and that of Fig. 5. When the firing ceases the nose 14 of the part 15 (which can be the piston of the firearm) hooks onto the nose 13 of the sear 4 which then tends 70 to be carried towards the right (position of Fig. 6) at the same time as the assembly 8-6. This movement is damped by the elements 2 which, in this case, bear against the head 1 which itself bears with its end 10 against the fixed abutment 9.

75 In this embodiment, a sear spring 17 is inter-

posed between the sear 4 and the sliding member 6, that is to say between two members which move simultaneously.

In the modification of Fig. 7, the mechanism of the firearm acts on the member 1 through the instrumentality of a lever 20 rocking about a fixed pin 21 and pivotally mounted at 22 on the said member 1.

The sliding member 6 acts on the same member through the instrumentality of its heel 7. 10 It will be noted that, in this case, the mechanism of the firearm and the sliding member compress the resilient element 2 always in the same direction, said element bearing against the threaded plug 11. 15

Fig. 8 shows another embodiment in which the sliding member is replaced by a lever 6 fol- 20 crumed about a fixed pin 23. The pin 5 of the sear 4 is carried by one of the arms of said lever, the other arm of which is in contact with a sleeve 20 7 against which the resilient element 2 acts. Said lever 6 plays exactly the same part as the sliding member 6 of the preceding figures, that is to say that when the firing ceases, the forward move- 25 ment of the sear is damped owing to the fact that said lever 6 compresses the resilient element 2.

In the embodiment of Fig. 9, the pin 5 of the sear is also carried by one of the arms of a lever 6, the other arm of which is engaged, with a 30 clearance J, in a slot of the member 1 integral with the member 7. Said clearance permits the free operation of said member as an accelerator during the firing. When the firing ceases the upper arm of the lever 6 tends to move towards 35 the left compressing the elements 2 which thereby ensure the damping of the forward movement of the sear.

The lever 6 has a third arm 25 on which acts the sear spring 17 and which also serves as an 40 abutment for the lever 6.

The embodiment of Fig. 10 differs from the preceding one by the arrangement of the lever 6, which in this case acts on the resilient elements 2 45 in the opposite direction to the member 1.

As has already been explained all these em- 50 bodiments have only been described and illus- trated in a purely explanatory and in no way limitative manner and they can be subjected to any useful modifications without exceeding the scope of the present invention.

We claim:

1. Automatic firearm comprising a mechanism having a reciprocating movement, a longitudinally sliding member, a sear for stopping the fir- 55 ing pivotally mounted on said member, a heel carried by said member and against which the breech mechanism abuts at the end of its recoil stroke, housings provided in said member and, in each of said housings, resilient means interposed 60 between an accelerator member mounted at one end of said housing and adapted to be carried rearwardly by said sliding member to compress the resilient means at the end of the stroke of the recoil mechanism of the firearm and a mov- 65 able heel mounted at the other end of said housing and adapted to be carried forwards by said sliding member when the firing is stopped, a fixed abutment being provided against which said movable heel abuts when the accelerator com- 70 presses said resilient means.

2. Automatic firearm comprising a mechanism having a reciprocating movement, a firing rate accelerator member adapted to be carried rear- 75 wards by the breech mechanism at the end of

its recoil travel, a member displaceable relatively to the breech mechanism, a sear mounted on said displaceable member and displaceable on the one hand substantially longitudinally and 5 on the other hand transversely for controlling the firing, a trigger for controlling the transverse movement of the sear, and a set of resilient elements co-operating with said accelerator member which compresses said elements in its 10 rearward movement and with said displaceable member which also compresses said set of resilient elements when the sear is carried forwards by the breech mechanism.

3. Automatic firearm comprising a mechanism 15 having a reciprocating movement, a firing rate accelerator member adapted to be carried rearwards by the breech mechanism at the end of its recoil travel, a member slidable longitudinally relatively to the breech mechanism, a sear pivoted on said slidable member, a trigger for rocking the sear, and a set of resilient elements co-operating with said accelerator member, which compresses said elements in its rearward movement, and with said slidable member which likewise 20 compresses said set of resilient elements when it is longitudinally forwardly displaced by the sear.

4. Automatic firearm comprising a mechanism having a reciprocating movement, a firing rate 25 accelerator member adapted to be carried rearwards by the breech mechanism at the end of its recoil travel, a member displaceable relatively to the breech mechanism, a sear pivotally mounted on said displaceable member, a trigger for 30 rocking the sear, resilient means interposed between said accelerator member and a part moving in synchronism with the displaceable member, and abutments on which the resilient elements bear in both directions.

40 5. Automatic firearm comprising a mechanism having a reciprocating movement, a firing rate accelerator member adapted to be carried rearwards by the breech mechanism at the end of its recoil travel, a member slidable longitudinally 45 relatively to the breech mechanism, a heel carried by said slidable member, a sear for controlling the firing pivotally mounted on said slid- 50 able member, a trigger for rocking the sear, and resilient means interposed between said heel and said accelerator member.

55 6. Automatic firearm comprising a mechanism having a reciprocating movement, a firing rate accelerator member adapted to be carried rearwards by the breech mechanism at the end of its recoil travel, a member displaceable relatively to the breech mechanism, a sear mounted on said displaceable member and displaceable on the one hand substantially longitudinally and on the other hand transversely for controlling the firing, a trigger for controlling the transverse 60 movement of the sear, a set of resilient elements co-operating with said displaceable member which compresses said elements in its rearward movement and with said displaceable member 65 which likewise compresses said set of resilient elements when the sear is carried forward by the breech mechanism, and a sear spring interposed between an arm of the sear and a swivel pressed against a fixed part of the firearm.

70 7. Automatic firearm comprising a mechanism

having a reciprocating movement, a firing rate accelerator member adapted to be carried rearwards by the breech mechanism at the end of its recoil travel, a member displaceable relatively to the breech mechanism, a sear mounted 5 on said displaceable member and displaceable on the one hand substantially longitudinally and on the other hand transversely for controlling the firing, a trigger for controlling the transverse movement of the sear, a set of resilient elements co-operating with said accelerator member which compresses said resilient elements in its rearward movement and with said displaceable member which likewise compresses said set of resilient elements when the sear is carried forwards by the breech mechanism, and a sear spring interposed between an arm of the sear and a part moving in synchronism with the sear. 10

8. Automatic firearm comprising a mechanism having a reciprocating movement, a firing rate 15 accelerator member adapted to be carried rearwards by the breech mechanism at the end of its recoil travel, a pivoting member mounted on a fixed pivot and a sear having a trunnion eccentric relatively to said fixed pivot pivotally 20 mounted on said trunnion, whereby said sear is displaceable on the one hand substantially longitudinally and on the other hand transversely for controlling the transverse movement of the sear, a set 25 of resilient elements co-operating with said accelerator member which compresses said elements in its rearward movement and with said pivoting member which likewise compresses said set of resilient elements when it is rocked by the sear. 30

9. Automatic firearm comprising a mechanism having a reciprocating movement, a firing rate accelerator member adapted to be carried rearwards by the breech mechanism at the end of its recoil travel, a lever pivoting on a fixed 35 fulcrum and having a trunnion eccentric relatively to said fulcrum, a sear pivotally mounted on said trunnion, whereby said sear is displaceable on the one hand substantially longitudinally and on the other hand transversely for controlling the 40 firing, a trigger for controlling the transverse movement of the sear, resilient means interposed between said accelerator member and said lever and adapted to be compressed by each of these two members, and fixed abutments for limiting 45 the movements of said two members.

10. Automatic firearm comprising a mechanism having a reciprocating movement, a first lever pivoting on a fixed fulcrum and displaced by the breech mechanism at the end of its recoil travel, a second lever pivoting on a fixed fulcrum and having a trunnion eccentric relatively to said fulcrum, a sear pivotally mounted on said trunnion, whereby said sear is displaceable on the one hand longitudinally and on the other hand 55 transversely for controlling the firing, a trigger for controlling the transverse movement of the sear, resilient means interposed between the two free ends of said two levers and adapted to be compressed by said levers, and fixed abutments 60 limiting the pivoting movement of said two levers. 65
